WATER FOWL DECOY

George H. Schwartztrauber, 925 9th St.,
West Des Moines, Iowa 50265

Filed Oct. 10, 1972, Ser. No. 296,083

Term of patent 14 years

Int. Cl. D22—05

U.S. Cl. D22—21

FIG. 1

FIG. 4

FIG. 2

FIG. 3

FIG. 5

FIG. 1 is a side elevational view of a water fowl decoy showing my new design;

FIG. 2 is a top plan view of FIG. 1;

FIG. 3 is a bottom plan view of FIG. 1;

FIG. 4 is a front elevational view of FIG. 1; and
FIG. 5 is a rear elevational view of FIG. 1.

I claim:

The ornamental design for a water fowl decoy, substantially as shown and described.
